UNITED STATES PATENT OFFICE.

CHARLES L. GOODRUM, OF NEW YORK, AND OSCAR F. FORSBERG, OF YONKERS, NEW YORK, ASSIGNORS TO WESTERN ELECTRIC COMPANY, INCORPORATED, OF NEW YORK, N. Y., A CORPORATION OF NEW YORK.

AUTOMATIC TELEPHONE SWITCH.

Application filed April 30, 1923. Serial No. 635,490.

To all whom it may concern:

Be it known that we, CHARLES L. GOODRUM and OSCAR F. FORSBERG, citizens of the United States, residing at New York, in the county of New York, State of New York, and Yonkers, in the county of Westchester, State of New York, respectively, have invented certain new and useful Improvements in Automatic Telephone Switches, of which the following is a full, clear, concise, and exact description.

This invention relates to automatic and semi-automatic telephone switches. More particularly, it refers to coordinate switches such as are used for establishing connection in a telephone exchange system of the type disclosed in British Patent No. 183,438, issued to Western Electric Company Ltd., accepted September 6, 1923, in which the present invention is particularly well adapted for use.

The object of the invention is to provide an improved form of coordinate switch which will be simple, efficient and in which the parts of the operating mechanism are readily accessible for adjustment or repair.

A feature of the invention resides in the provision of unitary sets of flat contact springs arranged on insulating supports and insulating cards for holding them in spaced non-contacting relation.

Another feature is the provision of a novel operating mechanism for actuating the horizontal bars whereby the lifting members carried thereby are moved into operating relation with the operating card through the sequential movement of a plurality of magnet armatures.

Another feature is the provision of a jointed selecting bar in which the loose motion of the joints is eliminated by means of a spring attached to its upper end and disposed to act against the pull of the magnet in order to keep the operating members carried thereby in alignment.

Another feature is the provision of flexible armatures for operating the vertical bars whereby the angular distance of each bar is controlled by means of stopping members independently of the stroke adjustment of its operating electromagnetic means.

Other features of invention and advantages will appear from the following de-

scription, and by the claims appended thereto, reference being had to the accompanying drawings in which Fig. 1 is a top sectional view of a portion of said switch, Fig. 2 is a left-hand side view thereof, Fig. 3 is a front assembly view of a set of active and passive contacts showing a selecting arm in cross section viewed approximately on line 3-3 of Fig. 1, Fig. 4 is a front sectional view of the same contact set but taken on line 4-4 of Fig. 1, Fig. 5 is an enlarged cross section view of the selecting arm taken approximately on line 5-5 of Fig. 1, showing diagrammatically the sequential movement of the lifting members, Fig. 6 is a sectional view of an operating bar taken approximately on line 6-6 of Fig. 1, Fig. 7 is a sectional view of an operating bar showing the position of the armatures relative to their respective operating electromagnets, taken approximately on line 7-7 of Fig. 1, Fig. 8 is a top view of the selecting bar with the coupling shown in cross section taken approximately on line 8-8 of Fig. 2.

The switching structure shown in Figs. 1 and 2 generally comprises a plurality of unitary sets of active and passive contact springs arranged on the insulating supports 10 rigidly fastened on the switch frame (not shown).

Each contact set comprises a number of stationary contact springs 11, 12, 13 and 14 which are associated with a corresponding number of movable contact springs 15, 16, 17 and 18, respectively. The active and passive contacts of each set are located in engageable relation in rectangular shaped slots 19 and 20 of a stationary card 21.

The cards 21 are each fixedly arranged on two laterally extending arms 23 and 24, integrally formed with the reinforcing plates 25 and 26 which are rigidly fastened on two opposite sides of supports 10 by any suitable fastening means.

The operating card 22 is slidably arranged between the stationary card 21 and the inwardly bent portions 25 and 26 of arms 23 and 24, respectively.

The insulating supports 10 may carry any number of unitary sets of contact springs 11, 12, 13, 14 and 15, 16, 17, 18, etc., and the switch structure may comprise any num-

ber of supports 10, depending upon the switch capacity desired.

For each horizontal row of contacts there is provided an operating bar 27 having a number of laterally extending arms 28, and on each arm 28 there is provided a lifting member 29 which has one end hooked on the bar 27 and held in adjusted position on arm 28 by means of a screw 30 and a stop 31.

For each vertical row of contacts, there is provided a selecting bar 32 provided with a number of arms 33. It is to be noted that normally the lifting members 29 are free to move in a vertical path without engaging the cards with which they are associated as shown at 51 in Fig. 3.

For convenience in assembling the switch, the selecting bar 32 is preferably made of a number of relatively short bars which are disposed coaxially and coupled by means of a universal joint 34, shown in Fig. 2. The universal joint 34 shown in cross section, Fig. 8, generally comprises a sleeve 57 having two holes drilled at right angles relative to each other and adapted to receive the pins 55 and 56, each of which is adapted to operatively connect its respective bar 32 to the sleeve 57. On the lower end of bar 32, there is rigidly secured an arm 35, disposed in operable relation with a resilient armature 36 associated with an electromagnet 37. The arm 38 which is an extension of arm 35 is rigidly secured on the bar 32 and engages an adjustable stop 39 provided for limiting the movement of the bar 32 in normal non-operating position against the resistance of a spring 40 acting on a pin 54 secured to the upper end of rod 32 and adapted to hold the arms 33 in alignment. Therefore, by means of this combination of parts, it is seen that the coupling pins 55 and 56 do not need to be tightly adjusted in order to hold the arms 33 in alignment for the looseness of the pins is automatically taken up by the tension of spring 40 which holds the bars and coupling tensioned against the stop 39 and its operating armature 36. An adjustable stop 41 is provided for limiting the movement of the bar 32 in adjusted position with reference to the lifting members 29 served thereby against the resistance of the resilient armature 36 whereby the angular distance of the bar 32 may be adjusted independently of the stroke of its operating electromagnetic means.

For each bar 27 there is provided a pair of armatures 42 and 43 adapted to rotate the bar in response to the successive energization of electromagnets 44 and 45. Magnet 44 is associated with armature 42 which is pivotally arranged on the bar 27 and held in adjusted position relative to its operating magnet by means of an adjustable stop 46.

Magnet 43 is associated with armature 45

which is rigidly fastened on the bar 27 by means of a number of rivets 47. A stop 48 arranged on a portion of the switch frame is provided to hold the bar in normal non-operated position against the resistance of the retracting spring 49, hooked on the downward extending lug 50 of the bar 27 shown in Figs. 6 and 7.

The sequential movement of the lifting members, relative to the operating cards, is shown diagrammatically in Figs. 3 and 5 wherein the lifting member 29 is shown in normal non-operated position. When the bar 27 is moved one step through the energization of magnet 44, the lifting members thereon are moved in operating relation with their associated arms 33, as shown at 52 in Fig. 3, whereupon the movement of the selecting bar 32 moves the lifting members in operating relation with the operating cards 22, as shown at 53. The second step of bar 27 imparted through the energization of magnet 45 is thereby effective to lift the operating card for engaging the contact springs and to move the lifting members in positions wherein any subsequent movement of the selecting bar 32 is ineffective to disturb the connection already established.

What is claimed is:

1. In a switching device, the combination of disengaged contacts, an operating bar therefor, electromagnets for operating said bar, a resilient member carried by said bar and movable sequentially in a plurality of coordinate directions for operating said contacts.

2. In a switching device, the combination of sets of disengaged contacts, a rotatably operating bar therefor, an arm integrally formed therewith, an operating member supported thereby and movable in separate steps in a plurality of coordinate directions, a rotatable bar having means for operating said member whereby it is effective to cause the interengagement of said contacts.

3. In a switching device, the combination of disengaged sets of contacts, an operating mechanism therefor comprising a bar, a pair of magnets for actuating said bar step by step, resilient members carried by said bar and movable sequentially in different directions, another bar for moving said members in one of said directions after the first step of the first mentioned bar, another magnet for operating said bar a second step for engaging said contacts.

4. In a switching device, sets of normally disengaged active and passive contacts arranged on an insulating support, reinforcing plates on each side of said support, an arm laterally extending from each of said plates, a card fixedly arranged on said arms for holding said contacts in engageable relation, a movable card arranged on said supports for operating said active contacts, and

means sequentially operated for moving the second mentioned card to effect the interengagement of said contacts.

5. In a switching device, sets of normally disengaged active and passive contacts arranged in coordinate rows on insulating supports, a selecting mechanism therefor, comprising a stepping bar for each row of said active contacts, operable members carried by each of said bars and normally movable step-by-step in a path wherein they are ineffective to engage contacts, a bar common to said members in one of said rows and means thereon for operating any one of said members with reference to said contacts, and another magnet for rotating the stepping bar another step to cause the interengagement of said active and passive contacts.
- 20 6. In a switching device, a plurality of sets of active and passive contacts arranged in coordinate rows, a pair of coordinately disposed bars therefor, means for rotating one of said bars in a number of steps, magnetic means for operating the other bar to render the movement of the stepping bar effective with respect to said active contacts.

7. In a coordinate switch structure, a row of unitary sets of normally disengaged active and passive contacts disposed in a common plane, a step-by-step movable bar common to said sets, a plurality of arms integrally formed therewith, one for each of said sets, an operable member on each of said arms movable in plane at right angles to the longitudinal axis of said bar, a selecting bar for each of said sets and means carried thereby for moving one of said members in said plane after the first movement and while the first mentioned bar is at rest, and means for operating the last mentioned bar another step for causing the interengagement of said active and passive contacts.

8. In a coordinate switch structure, coordinately disposed rows of unitary sets of disengaged active and passive contacts, a mechanism for selectively engaging said contacts comprising a stepping bar for each horizontal row of said contacts, operable members carried thereby, a selecting bar for each vertical row of said contacts, a magnet for operating the stepping bar one step to move said members in position wherein a movement of a vertical bar is effective to move one of said members in operative relation with a set of active contacts, another magnet for moving the stepping bar another step for engaging the contacts of that selected set.

9. In a switching device, a jointed select-

ing bar comprising a plurality of coaxially disposed bars, a plurality of fixed members carried by each of said bars, a coupling for operatively connecting said bars, an arm carried by one of said bars, a stop therefor, another arm carried by another bar, a retracting spring attached to the last mentioned arm for holding said members in alignment against said stop regardless of the looseness in the couplings.

10. In a coordinate switch structure, the combination of a plurality of unitary sets of disengaged active and passive contacts arranged in a row, a jointed selecting bar therefor, operating members arranged on said bar each associated with one of said sets, an armature attached on one end of said bar, an adjustable stop for limiting the movement of said bar, a retracting spring attached on the other end of said bar to hold said bar and operating members thereon in adjusted position regardless of the angular looseness in the joints.

11. In a switching device, disengaged contacts, an operable bar associated with said contacts, a stepping mechanism for rotating said bar comprising a magnet, an armature pivotally arranged on said bar and responsive to the energization of said magnet for rotating the bar one step, another armature securely arranged on said bar for moving said bar another step for engaging said contacts.

12. In a switching device, a selecting bar, an operating magnet therefor, a resilient armature, in operable engagement with said bar, and a stop for arresting said bar in adjusted position against the resistance of said armature when attracted by said magnet.

13. In a switching structure, the combination of normally disengaged stationary and operable contacts, an operating mechanism therefor comprising a bar, a plurality of electromagnetic means for moving said bar, step-by-step operable members carried by said bar and normally movable in a path wherein they are ineffective with respect to said contacts, another bar for moving said members in a direction at right angles to said paths after a movement of the first mentioned bar, means included in the first mentioned means for interengaging said contacts and for moving said members wherein any subsequent movements of the second mentioned bar is ineffective to disturb the connection already established.

In witness whereof, we hereunto subscribe our names this 26 day of April A. D., 1923.

CHARLES L. GOODRUM.
OSCAR F. FORSBERG.
